UNITED STATES PATENT OFFICE

GEORGE A. PICKUP, OF EAST NASHVILLE, TENNESSEE

RUBBER TIME STAMP AND DATER

Application filed June 27, 1927. Serial No. 201,843.

This invention relates to printing, and its general object is to provide a stamp that is capable of stamping the date and time and is adjustable for that purpose in an easy and expeditious manner with very little effort, yet will remain in its set position until manually changed.

The principal object of the invention is to provide a stamp of the changeable type as set forth, that is composed of rubber in all respects with the exception of the handle which is formed from wood and is detachably associated with the rubber parts.

A further object of the invention is to provide a time and dating stamp that includes an indicator so that the stamp can be set without referring to the stamping face thereof.

Another object of the invention is to provide a rubber stamp that is extremely simple in construction and inexpensive to manufacture.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a front elevation of the stamp forming the subject matter of the present invention.

Figure 2 is a top plan view showing the application of the time ring and the indicating finger thereof.

Figure 3 is a bottom plan view of the stamp as shown in Figure 2.

Figure 4 is a sectional view taken on line 4-4 of Figure 1.

Figure 5 is a top plan view showing the application of the date ring.

Figure 6 is a bottom plan view of the stamp as shown in Figure 5.

Referring to the drawings in detail the reference numeral 1 indicates the body of

the stamp which is formed from rubber and is provided with a recess 2 which in reality makes the body substantially hollow as best shown in Figure 4 of the drawings. Rising centrally from the top of said body is a projection 3 provided with a bore which registers with and forms a continuation of a bore extending through the body and terminating in the recess 2 and for distinction the bores as above set forth are indicated by the reference numeral 4.

The recess 2 is enlarged at its lower end to provide an annular shoulder 5 and disposed in the enlarged portion of the recess 2 and engaging the shoulder 5 is a disk 6 which is provided with an annular flange 7 arranged about its bottom portion as shown. The disk is fixed in the recess and the flange 7 thereof is disposed in engagement with a ring 8 which is shouldered to secure said disk to the body and is mounted for rotation on the disk and said ring is formed with an annular recess having a flat bottom wall 9 and a downwardly tapered upper wall 10 so as to accommodate a like shape flange 11 formed on the body as best shown in Figure 4 of the drawings.

The construction of the dating ring and time ring is similar with the exception of course that the date ring is provided with numerals indicating the days of the month and which as shown in Figures 5 and 6 are disposed upon the upper and lower surfaces thereof, while the time ring is provided with numerals which indicate the hours of the day and are likewise disposed, as best shown in Figures 2 and 3 of the drawings. The rings are interchangeable and can be associated with the flange 11 at the will of the operator, and when disposed in the operative position as shown in Figure 4, it will be apparent that upon rotating the rings that the disk 6 will remain stationary and due to the engagement of the disk 6 with the rings, it will retain the rings in their adjusted positions. The numerals formed on the upper surface of the ring are arranged on a raised portion 12 and cooperating with these last mentioned numerals is a finger 13 which is integrally formed with

the body 1 and projects therefrom in a manner to overlie the figures in the rotation of the rings, so that the stamp can be set without referring to the stamping surface thereof. The numerals formed on the bottom of the rings are disposed upon the surface of a depending portion 14 and extending outwardly from the raised portion 12 and depending portion 14 is a ribbed flange 15 which provides a gripping surface so that the stamp can be set with very little effort on the part of the operator.

The disk 6 may be provided with any words desired, but in the present instance 15 the word "Received" is formed on the bottom surface of the disk together with a pointer which is indicated by the reference numeral 16. The pointer cooperates with the numerals on the lower face of the rings 20 and is of course aligned with the finger 13 for the obvious purpose of pointing to the number set on the stamp. The disk 6 is also provided with a groove 17 which may receive rubber type bearing legends P. M. 25 or A. M. when the ring bearing the time numerals is associated with the body, but of course when the ring bearing the numerals of the month is arranged on the body, the slot 17 is adapted to have arranged 30 therein type which bear the name of the month and the year.

The upper surface of the body 1 is slightly raised and this raised portion is provided with a flat upper surface which surrounds 35 the projection 3 and is adapted to accommodate the lower surface of the handle 18 which is formed from wood and includes a recess to receive the projection 3, and the handle is secured to the body through the 40 instrumentality of a screw 19 passing through the bores 4 and embedded in the handle as best shown in Figure 4 of the drawings. The screw 19 is of the usual kerfed head variety and is provided with a 45 washer 20 so that the head will not damage the body 1 in fixing the same to the handle.

From the above description and disclosure of the drawings, it will be obvious that the stamp which forms the subject matter 50 of the present invention is extremely simple in construction, and is adjustable and interchangeable so that it is capable of stamping the time and date in a clear manner notwithstanding the fact that the stamp includes a wooden handle which of course adds 55 to its strength and makes the same substantially rigid whereby it can be easily handled and prolongs the life of the stamp as will be readily apparent.

60 It is thought from the foregoing description that the advantages and novel features of my invention will be readily apparent.

I desire it to be understood that I may 65 make changes in the construction and in the combination and arrangement of the several

parts, provided that such changes fall within the scope of the appended claim.

What I claim is:

A time and dating stamp of the character described comprising a hollow rubber body, a flange formed on said body at its lower end, a substantially rigid handle secured to said body at its upper end, rubber rings, one having indicia representing the days of the month, and the other having indicia representing the time of the day, said rings being removably mounted on the flange for rotation and interchangeable with each other, a ribbed flange formed about the periphery of each ring, a rubber disk secured to the lower end of said body through the medium of either of the rings, a pointer carried by said disk and being associated with said numerals, and an indicator formed on said body and cooperating with said pointer.

70 In testimony whereof I affix my signature.

GEORGE A. PICKUP.
